UNITED STATES PATENT OFFICE.

BERNARD H. SKELLY, OF BRIDGEPORT, CONNECTICUT.

TRAFFIC SIGNAL FOR AUTOMOBILES.

Application filed August 7, 1923. Serial No. 656,159.

To all whom it may concern:

Be it known that I, BERNARD H. SKELLY, a citizen of the United States, residing at the city of Bridgeport, in the county of Fairfield and State of Connecticut, have invented certain new and useful Improvements in Traffic Signals for Automobiles; and I do declare the following to be a full, clear, and exact description of the invention, such as 10 will enable others skilled in the art to which it appertains to make and use the same.

This invention relates to a traffic signal for automobiles, but has particular reference to a signal that is carried at the rear 15 of an automobile and is operable to give warning to a machine in the rear.

Automobile signals of this sort have heretofore been provided, but they are efficient only when they are noticed, and there has 20 been nothing in their makeup that would catch the eye of an oncoming driver, and many drivers would travel in the rear of another car or would pass many cars, without noticing whether these cars were or 25 were not equipped with traffic signal devices.

It is the especial object of this invention to identify the signal with that which is never ignored by an automobile driver, 30 namely, a traffic officer, or, to be more specifically correct, the image or effigy of a traffic officer, and furthermore, to associate this effigy with a fac-simile of the usual standard that bears the notices "Stop" and "Go."

In further carrying out a replica of a traffic officer and the standard bearing the above 35 designated notices, the right arm of the effigy is pivoted so as to be capable of swinging outwardly in imitation of the usual 40 warning stop signal given by the officer, and the standard has reciprocatory rotary movements so that it may be turned to expose the "Stop" or the "Go" signal, the former being exposed when the arm of the effigy is 45 swung outwardly, while the latter is exhibited only when said arm is dropped.

The accompanying drawings illustrate the 50 invention as operated direct from the foot brake, although it will be readily understood from the description which follows that the actual agency which controls the operation is immaterial.

In these drawings—

Figure 1 is a rear view of an automobile 55 equipped with the invention.

Figure 2 is a horizontal sectional view of the base or platform with the cover partly broken away and showing the operative parts in normal position.

Figure 3 is a section at the line 3—3 of 60 Figure 2.

Figure 4 is a view similar to Figure 2, but showing the position of parts when the signal has been operated to exhibit the warning. 65

Figure 5 is a section at the line 5—5 of Figure 4.

Figure 6 is a detail rear view of the traffic officer effigy partly broken away and sectioned to show the operation of the signal 70 arm when raised.

Figure 7 is a detail rear view of both the traffic officer effigy and the notice bearing standard, said effigy being partly broken away and sectioned to show the appearance 75 of parts when the signal arm is lowered, and.

Figure 8 is a section at the line 8—8 of Figure 7.

Similar numerals of reference denote like 80 parts in the several figures of the drawing.

1 is a hollow platform or base which is secured to the rear portion of an automobile in any suitable manner.

2 represents an image or effigy of a traffic 85 officer mounted on said base, and having the right arm 3 pivoted at its upper end within the shoulder portion of the effigy. While this pivoting of the arm may be effected in various ways, it is preferred to bifurcate the 90 arm as shown at 4 and to secure these bifurcations to a spool 5 by means of a pin 6 driven through said bifurcations and spool, and to pass a pivot pin 7 through the shoulder of the effigy loosely within these bifurcations and the spool, as shown at Figure 95 8, thus affording a pivoted connection which is neat and will permit the signal arm to swing readily.

The right leg of the effigy is hollow, and suitable draft means, such as a cord 8, is secured in such manner to the spool 5 and then wrapped around the latter throughout a part of its periphery and finally passed down through said hollow leg, so that a pull 105 on the cord will cause the signal arm 5 to be elevated as shown at Figures 1 and 6, while the position of these parts when the signal arm is lowered is shown at Figure 7.

The right foot of the effigy has its heel por- 110

tion 9 secured to the base 1 by means of a hollow bolt 10 which is passed through the cover of the base and secured by nut 11, and the cord 8 passes through this bolt out 5 through a bushing 12 that is secured to the inner side wall of the base, and is secured to a ring 13.

14 is a vertical standard having fixed to its upper end the usual rectangularly disposed notices "Stop" and "Go," and the lower end of this standard is stepped within 10 a rotary bushing 15 and secured rigid therewith by means of set screws 16. This bushing is formed with a large circular upper 15 portion *a* and a comparatively small circular lower portion *b*, and these two circular portions are journaled respectively within the top and bottom of the base 1.

The bushing intermediate these circular 20 portions is square in cross section and is forced through a corresponding opening in a spool 17 to the sides of which are affixed metal cheek plates 18 that extend beyond the spool, so that it will be clear that said 25 bushing, spool and cheek plates are all rigidly secured together.

A suitable draft means, such as a cord 19, is secured in such manner to this spool 17 and then wrapped around the latter for 30 a part of its periphery and finally passed through a bushing 20, secured to the inner side of the base 1, and secured to the ring 13, that a pulling of said ring will simultaneously cause the signal arm of the effigy 35 to be raised and the standard to be turned to expose the "Stop" notice, while a release of the ring will permit the arm and standard to be returned to normal positions owing to the action of the spring 21, one 40 end of which is attached to the base while the other end is attached to the face of the upper cheek plate 18 near its periphery, and in this connection attention is called to the cutting away of the cheek plates to provide shoulders *c*, *d*, which strike the pin *e*, fixed in the base, when the pull on the cords or the release of the latter respectively effect the warning signal and notice and the restoration of parts to normal positions.

50 The left arm of the effigy is extended and its hand loosely encircles the standard so as to steady the latter, the effect being to make it appear that the effigy turned the standard when it raised its signal arm.

55 The ring 13 is connected to the brake rod or any part associated therewith by any suitable draft means, such as a cord 22, so that when the brake is operated the signal arm and standard will be actuated in the manner above described.

60 If desired, the draft means 22 may be led over ordinary anti-friction devices, such as pulleys, through the automobile dash and provided with any suitable ring or analogous 65 means convenient for grasping, so that the

driver can manually operate the signal whenever he sees fit.

When in traffic crowded streets, the driver of an automobile is constantly operating his 70 brake, and therefore the latter is the most advantageous agent for controlling the operation of the signal. When the brake is put on, the arm of the image is swung outwardly and the standard rotated to expose the notice "Stop", and when the brake is relaxed the arm will return to normal position and the spring element will cause the return rotation of the standard so as to exhibit the notice "Go".

A traffic officer usually grasps the standard 80 with his left hand and manipulates the "Stop" and "Go" signs, while in the present instance, the replica is carried out by loosely supporting the standard within the hand of the effigy, the "Stop" and "Go" 85 signs being rigidly carried by the standard, as heretofore set forth.

This carrying at the rear of an automobile of a traffic signal that is an exact 90 replica of a traffic officer both as to appearance and action, will invariably attract the attention of the driver of a machine in the rear of the signal, and, moreover, the signal is a striking novelty, and its actions are so 95 associated with the familiar raising of the arm and the operation of the instruction notice by an actual traffic officer, that automobile drivers, schooled to obey the officer, are naturally urged to instantly heed the signal.

The particular means shown and described herein for operating the signal arm and the standard is immaterial, since the effigy itself and the raising of the signal arm and the turning of the standard are the real essential features of the invention, and the system of cords, and their connection with said arm and standard exemplify only one way of providing for the proper operation 105 of the device.

110 It is unnecessary to show and describe all the ways in which the device may be successfully operated, and the terms "cord" and "draft means" used in some of the appended claims are employed in their broadest sense.

115 If desired, the effigy may be utilized without the standard, although it is preferred to use the two together, since jointly they form a true and startling duplication of 120 actual traffic regulating means commonly seen in large cities. The usual white light carried at the rear of the automobile for illuminating the registration number will amply light up the effigy and standard so 125 that the workings thereof will be visible at night, or, if desired, a special light may be provided, or the effigy itself might be made from some translucent material and a light located therein.

Having thus described my invention what I claim is:—

1. An automobile traffic signal, consisting of an effigy of a traffic officer carried on the rear of the automobile and having a signal arm pivoted at the shoulder so as to be capable of upward and outward swinging movements, a rotary notice bearing standard in proximity to said effigy, the other arm 10 of the latter being extended with the hand loosely embracing the standard, and means under the control of the automobile driver and operatively connected with the signal arm and with the standard for rotating the 15 latter to exhibit the proper notice and for simultaneously raising the signal arm.

2. An automobile traffic signal, consisting of an effigy of a traffic officer carried on the rear of the automobile and having a signal 20 arm pivoted at the shoulder so as to be capable of upward and outward swinging movements, a cord secured to the shoulder portion of said arm and led downwardly through an office that opens toward the 25 front of the automobile and is carried by the base of the effigy, a vertical standard journaled in said base, and loosely embraced by the hand of the other arm of the effigy and carrying at its upper end the conventional 30 notices "Stop" and "Go," draft means attached to said standard or an element connected thereto whereby the pulling of this draft means will cause the rotation of the standard, connections between the 35 foot brake of the automobile and said draft

means whereby the application of the brake will exert a pull on the latter and effect the simultaneous raising of the signal arm and the turning of the standard, and spring means for returning the standard to normal 40 position after the brake has been released.

3. An automobile traffic signal, consisting of an effigy of a traffic officer carried on the rear of the automobile and having a pivoted signal arm capable of being swung from the 45 shoulder upwardly and outwardly, a vertical rotary standard bearing the conventional notices "Stop" and "Go," and means controlled by the automobile driver for simultaneously operating said arm and 50 standard.

4. An automobile traffic signal, consisting of the effigy of a traffic officer carried on the rear of the automobile and having a pivoted signal arm capable of being swung from the 55 shoulder upwardly and outwardly, a vertical rotary standard bearing the conventional notices "Stop" and "Go" and loosely embraced by the hand of the other arm of the effigy, connections between the foot 60 brake of the automobile and said signal arm and standard whereby the application of the brake will effect the simultaneous raising of said arm and turning of said standard, and means for automatically returning 65 the parts to normal position after the brake has been released.

In testimony whereof I affix my signature hereto.

BERNARD H. SKELLY.
